above application, Ser. No. 594,503.

ABSTRACT OF THE DISCLOSURE

A multiple pushbutton switch comprising a frame of one-piece construction, providing a series of slots, stationary contact assemblies mounted in the slots, and slide members having contacts adapted to engage the stationary contact assemblies. The contact assemblies include contact plates juxtaposed to provide oblique slits therebetween, and the slide contacts comprise W-shaped members with their bottom corner parts adapted to bridge the slits.

This invention relates to a multiple pushbutton switch.

A primary object of the present invention is to provide a multiple pushbutton switch comprising a compact and simple frame of synthetic resin and plurality of slide switches.

Another object of the present invention is to provide a switch which may be built up easily and quickly.

A further object of the present invention is to provide a switch having an elastic movable contact deformed in shape of W which would be inserted elastically into a groove of a slide rod in a switch unit.

These and other objects of the present invention and the various features and details of the operation and construction thereof are hereinafter more fully set forth and described with reference to the accompanying drawings, in which:

FIGURE 1 is a front view of a frame of a multiple pushbutton switch in accordance with the present invention;

FIGURE 2 is a plan view illustrating the frame of FIG. 1;

FIGURE 3 is a sectional view of the frame taken along line III-III of FIG. 1;

FIG. 4 is an enlarged sectional plan view of a part of the switch in accordance with the present invention, taken along line IV-IV of FIG. 5;

FIG. 5 is a sectional view of the switch taken along line V-V of FIG. 4;

FIG. 6 is a side view of a sliding rod for the switch of the invention;

FIG. 7 is a plan view of the sliding rod with a pushbutton;

FIG. 8 is an enlarged plan view of extended plate for movable contact which is to be attached in the groove of the sliding rod;

FIG. 9 is a perspective front view of the movable contact being formed from the extended plate;

FIG. 10 is an enlarged plan view of the switch; and

FIG. 11 is a sectional side view of another embodiment of the switch unit.

Referring now to FIGS. 1 to 3, a frame F is made of synthetic resin and molded in one body, and comprises a main frame 1 and plurality of branches 6. The main frame formed is L-shape in section as shown in FIG. 3, comprises an upright wall 2 and a horizontal wall 5. On the upper portion of the upright wall 2, notches 3 are formed at equally-spaced intervals, and on the upper side

of the upright wall 2, upstanding projections 4 are provided near each notch 3.

From the rear side of the horizontal wall 5 of the main frame 1, branches 6 are provided of equal height to the upright wall 2 to form a groove 5a between the upright wall 2 and branches 6. The branches are spaced along the length of the frame to provide slots in which stationary contact assemblies are mounted and which are aligned with the notches 3.

On the rear part of the upper side of each projecting branch 6, an upstanding projection 7 is provided on one side and a threaded hole 8 is provided on another side for the purpose of fixing the upper insulating plates 15. On each end of the horizontal wall 5, a connecting rib 9 having a hole 9a is elongated from the horizontal wall 5.

At the bottom of opposite side of the branches 6, supporting ribs 10 are provided to support the lower insulating plate 16 of the electric switch.

Referring to FIGS. 4 and 5, a stationary contact assembly 11 of the switch comprises a series of many stationary contact plates 12 which are in the form of a trapezoid having elongated projecting parts 13 and 14 on its opposite ends, an upper insulating plate 15 of wider size than the slots between the branches 6, to be attached to the projections 4 and 7, and a lower insulating plate 16 of equal width to the slots between the branches 6.

Said contact plates 12 are mounted reversely in side by side relation in two parallel rows between the insulating plates 15 and 16 so that every slit S produced between the contacts 12 is inclined oppositely to the insulating plates 15 and 16. The upper insulating plates 15, as shown in broken lines in FIG. 4, have three holes registering with, and to be engaged over the projections 4 and 7, and a hole registering with, and to be fixed by a screw 19 to, the threaded hole 8.

As shown in FIG. 6, a sliding rod 20 having a width to be slidably inserted between the rows of the stationary contacts 12 in the slot and projecting through the notch 3 as shown in FIG. 4 has a series of many longitudinal grooves 21 spaced inwardly along both sides of the upper portion, and the middle part of the outer wall of each groove is cut off to leave side end walls 24a and 24b adjacent both ends of the grooves 21. Two depressions 22 are formed at the ends and a small depression 23 is formed in the middle after each groove 21.

A metal contact plate 24 having legs 25, 26 and 27 shown in FIG. 8 is bent in the form of character W, the height of which is a little higher than the width of the groove as shown at A in FIG. 10 and the tops of the W-shaped contacts 24 thus formed are inserted as at B into the grooves by bending the ends elastically to engage behind the side end walls, and legs 25, 26 and 27 are inserted in the depressions 23, 22 and 22 respectively, and thus the metal contacts 24 are supported elastically in the grooves 21.

On the neck of the sliding rod 20, a pair of V-shaped cuts 28, 29 are provided in one side, and on the end 30 of the rod, there is provided ears 32 to fix a pushbutton 31 on its end. A projection 33 is on the bottom side of the rod 20 to keep the slide rod 20 from running away from the stationary insulating plate 16.

The switch unit is so made that the sliding rod 20 may be inserted slidably between the rows of the fixed contacts 12, and the contacts 24 bent as B in the groove is then deformed elastically, as permitted by the groove 21 as C, between the rows of the contacts 12 (FIG. 10), and both ends of the W-shaped contacts become free from the side walls 24a and 24b and the W-shaped contact is supported by the top corner part 25a and the two bottom corner parts 26a and 27a as shown in FIG. 10.

A metallic slide bar 35 (see FIGS. 2 and 4) having projections 36 equally spaced therealong is provided in the

groove 5a between the upright wall 2 and the branches 6 so as to be pushed in one direction by a spring 38 mounted in the recess 37 on the branch 6a. To this end, as shown in FIG. 3, the switch units are inserted between branches 6 and every lower insulating plate 16 is supported on ribs 10 and every upper insulating plate 15 is supported on the upright wall 2 and branches 6 by means of the holes 17, engaging over the projections 4 and 7 and a screw 19 engaging in the threaded hole 8, and a coil spring 39 is inserted between every button 31 and main frame 1.

When a pushbutton 31 is pressed against the coil spring 39, the slide rod 20 slides to change the connection of the contacts 12 and 24. When displaced inwardly past the projection 36, the rod 20 keeps in its position by means of the engagement of the cut 28 and the projection 36.

When another sliding rod is pushed, the metal bar 35 is shifted against the force of the spring 38 and the rod previously pushed is released to come back to its original position (shown in FIG. 4) by the spring 39 and the newly pushed sliding bar is caught in its inner position and thus, the connection is changed. Thus, in accordance with the present invention, the switch is of simple construction, small size and lightweight, and every part may be arranged to be built up by pressing, and switch units are fixed to the frame F by one screw 19 and needs no soldering or welding and capable of easy assembling.

FIG. 11 shows another embodiment of the fixed contact shown in FIG. 5. A contact plate 41 has a contact portion 42 of a parallelogram in its center portion and from the rim of the contact portion 42, stems 43 and 44 are projected perpendicularly in the opposite directions to make shoulders 45, 46 on both sides of the rim. The stems 43 and 44 have wedge-shaped portions 47 and 48 from which end portions 49 and 50 of narrow width are elongated. Upper and lower insulating plates 15 and 16, as explained above, have a series of equally spaced holes 51 and 52, and the end portions 49 and 50 are inserted into and pasted and fixed rigidly to the upper and lower insulating plates 15 and 16. The contacts 42 are supported by their shoulders 45 and 46.

Therefore, the slits S between the contacts 42 on the stationary insulating plates 15 and 16 are of the constant width and the direction of the slits S are parallel to each other and inclined to the insulating plates 15 and 16.

When the slide rod 20 as explained above, is inserted between the rows of fixed contacts 42, contact lines 53 of the contact 24 as shown in FIG. 11 becomes perpendicular to the insulating plates 15 and 16.

When the sliding rod 20 is pushed to travel, the contact portions of the movable contacts 24 to the fixed contacts 42 may be slid over the inclined slits S and transmitted smoothly to the next contacts 42 without click motion or unbalanced contact for electric balance.

While particular embodiments of the present invention have been illustrated and described herein, it is not intended to limit the invention to such a disclosure, and changes and modifications may be incorporated and embodied therein within the scope of the following claims.

What is claimed is:

1. A multiple pushbutton switch comprising a one-piece frame of synthetic resin having a main frame and branches, said main frame being formed L-shaped in section by an upright wall and a horizontal wall, said branches being disposed in spaced relation along the rear side of the horizontal wall to form a transverse groove between the upright wall and branches, and longitudinal slots between adjacent branches;
- 15 switch units mounted in said slots and comprised of stationary parts with contact plates having inclined slits between them; and a slide rod having longitudinal grooves with slide contacts of W-shape, each contact having its top corner part and ends elastically inserted in the longitudinal groove of the slide rod so that the bottom corner parts project against said contact plates, said W-shaped contact being supported by the top and bottom corner parts between the slide rod and stationary contact plates.
2. A slide rod with a slide contact for a switch comprising a rod with a longitudinal groove spaced inwardly along the side thereof, and having inner and outer side walls and a base wall, the outer side wall being cut-out to leave side end walls adjacent both ends of the grooves, depressions being provided in the base wall at each end and a small depression being provided in the base wall in the middle; a metal contact bent in W-shape having two ends and a corner part on the top, and two corner parts on the bottom side of the contact, and three legs projecting from the top side, said contact being inserted into the groove by bending its ends elastically so that the legs rest in both end depressions and the middle depression respectively to be supported elastically in the groove.
